MOTION-TRANSMITTING MECHANISM

Bryan Brassell, Puerto de Luna, N. Mex.

Application July 16, 1941, Serial No. 402,652

14 Claims. (Cl. 103—205)

This invention relates to improvements in motion-transmitting mechanisms, and relates more particularly to mechanisms involving the driving of a reciprocating driven member and, more specifically, where the driven member is itself being driven by a reciprocating drive member.

The reciprocation of a driven member from a power source necessarily involves a number of problems, including those of length of stroke, speed, etc., but one of the major difficulties arises through the conditions presented in the end zones of reciprocation. In such zones the member must approach the extreme, come to a stop, and then begin travel in the opposite direction. Obviously, the greater the speed, the greater becomes the problem conditions, since the member ends its stroke at the same point regardless of speed, the latter determining the rapidity of approach and the rapidity with which the beginning of the succeeding stroke must take place.

The conditions can be readily understood by considering the driven member as the pump rod or actuator of a pumping system, with the rod moving vertically; assuming the system operating to pump in one direction, the approach to the lower extreme is made without load, the condition changing when the rod reaches its extreme position, the load becoming manifest at the beginning of the return stroke. The specific characteristics at the instant of change are those of first bringing the inertia of motion to a condition of inertia of rest and then immediately resuming the inertia of motion but with the latter in the opposite direction and with the load added. The speed will determine the time within which these changes can take place, so that the greater the speed of member movement the less becomes the time within which the change can be made.

After the succeeding inertia of motion has been established it is readily continued until the opposite end zone is reached. But during this period of transition during which the inertia of motion must be reversed in direction—with the intervening inertia of rest essential—is to be found one of the problems which are present—the resumption of the inertia of motion in the opposite direction (with the load added and increasing resistance) and in which the speed can determine whether or not the change can be made without shock.

In a companion application filed March 11, 1941, Serial No. 382,823, (U. S. Patent No. 2,273,173, issued February 17, 1942) conditions

such as this are presented, with the solution of the problems involved provided by the use of a reciprocating drive member operated by a suitable power source—preferably a rotating member connected with the drive member by suitable connections to thereby convert the rotary motion of the power source into reciprocatory movement of the drive member; the drive and driven members are connected by a leverage assembly designed to set up a differential in speed characteristic between the two members within the end zones of reciprocation of the drive member. The assembly therefore has the speed of the drive member controlled by the speed variations set up by the power source, while the speed of the driven member—the latter driven by the drive member through the leverage assembly with the leverage assembly partaking of the speed variations of the drive member—is varied from that of a one-to-one relation between the members, present in the intermediate zone, to an increasing differential during approach in the end zones, with the result that the speed of the driven member is reduced within the end zones.

The difficulties within the end zone can be understood by considering the effect of the travel of the power source—a crank-pin, for instance—through its dead center zones, such travel representing the approach, stop and reversal of the driven member in each of its end zones of reciprocation. During the arcuate travel of the crank-pin through such dead center zone, the pin approaches, reaches, passes, and then leaves a point which represents the extreme of reciprocation, with the pin moving continuously through the arc. Obviously, therefore, the period of time during which the crank-pin is positioned within such point is practically imperceptible, since it represents a single point in the circumference of the circle, and the approach to and succeeding advance from such point actually represent movements of the two strokes of the reciprocating member. Yet, if the cycle of the inertia of motion, inertia of rest, and inertia of motion in the opposite direction, is to be established, the inertia of rest must be obtained during this imperceptible period during which the crank-pin is passing the zenith or nadir points of its travel. Hence, the inertia of rest condition is more or less theoretical under conditions such as this.

While the arcuate path of the crank-pin through the dead-center zone represents but a short portion of the length of the reciprocating

stroke, yet such travel pertains to the condition of inertia of motion, excepting at such zenith or nadir point, and it is this fact that generally determines the speed of travel of the power source, the diameter of the crank-pin orbit, etc., in order that the approach to and recession from such point will not be at a too rapid rate; if the rate is rapid, there will be a tendency to produce shocks, especially where the driven member is of considerable length, etc., since the member must also pass through this cycle concurrently with the drive member. Hence, the speeds employed are designed to prevent such conditions of shock, or, if higher speeds are contemplated the attempt is made to cushion the shock by 15 springs, etc., with but partial success.

A fundamental of the present invention is based on the assumption that if the theoretical and imperceptible inertia of rest periods is prolonged into a dwell characteristic, certain of the difficulties of the end zone will disappear, due to the fact that the approach of the driven member will reach a definite end and produce a 20 complete rest status, and that the succeeding beginning of the inertia of motion movement in the opposite direction will take place under the more favorable conditions, since momentum, stretch, etc., will have become inactive as factors opposing the change in direction of motion, and the beginning of the return stroke will be opposed only by the load. The dwell is provided under conditions analogous to those of a lost-motion effect, set up by the action of the mechanism connecting the drive and driven members, and may be of a desired length, to ensure that the dwell period has become complete before beginning the succeeding stroke.

Since the dwell takes place while the crank-pin continues its movement in its orbital path, the pin will have passed the zenith or nadir point of the dead center positions at the beginning of the succeeding stroke of the driven member, so that the drive member will have begun such stroke prior to the beginning of activity of the driven member stroke in such direction. To avoid any difficulty as to speed under the changed conditions, the connecting mechanism between the drive and driven members is arranged in such manner as to set up a percentage speed relationship between the two members at the beginning of the driven member movement—thus providing a differential in speed value characteristic as between the members; this differential decreases in value as the two members advance until the differential reaches zero at a selected point in the length of the stroke, after which both members continue their travel in the one-to-one ratio to the end of the stroke.

The invention is preferably designed for service under double-acting pumping service conditions—conditions where each stroke of the drive member is a pumping stroke; under such conditions both strokes of the member are made in presence of resistance effects of general similarity, and it is possible to set up uniform operating conditions to ensure the proper operation of the assemblage.

As will be understood, the cycles of the drive and driven members vary from each other due to the particular arrangement. The cycle of the drive member is determined by the movement of the power source, so that such member reaches the ends of the stroke when the crank-pin is in its zenith and nadir positions, the speed of the member between these points following the var-

iations set up by the movement of the crank-pin through its orbit. However, the cycle of the driven member is varied from this through the fact that its beginning is delayed, the speed at the beginning is lower, and then increased at a greater rate than that of the drive member until both members are brought to similar speeds, after which both travel to the end of the stroke at such one-to-one speed relationship.

In the latter respect, the present invention differs from that of the companion application, in that the development of the speed differential during the approach period is omitted, the driven member reaching the end of the stroke concurrently with and at the same speed as the drive member. This is made possible through the presence of the dwell characteristic referred to, and which permits the driven member to come to a complete rest before beginning the succeeding stroke. Hence, the rapidity of advance during approach can not only be increased with safety, but can be made at a more rapid rate than is usually considered possible, especially 25 under the conditions of the double-acting pumping systems. In other words, the latter system can operate with safety at considerably higher power speeds and without the necessity of cushioning structures, etc., thus increasing the capacity and efficiency of such systems.

While the system is particularly adapted to pumping systems of the double-acting type, it is not limited in action in this respect, the mechanism being such as will permit its use with 30 single-acting pumping systems as well, the arrangement being such that with either type, it is possible to operate the system under higher speeds without loss of efficiency, or to increase efficiency at the lower speeds.

To these and other ends, therefore, the nature of which will be more fully disclosed as the invention is hereinafter particularly described, said invention consists in the improved construction and combination of parts as more particularly 40 described in detail hereinafter, illustrated in the accompanying drawings, and more particularly pointed out in the appended claims.

In the accompanying drawings, in which similar reference characters indicate similar parts in each 45 of the views—

Figure 1 is a diagrammatic view showing a power source, drive, and driven members, with the elements operatively connected to produce the results indicated;

Figure 2 is a similar view, on an enlarged scale, showing the controlling portions of the unit which 55 operatively connects the drive and driven members, the leverage carrier being illustrated in a number of different positions;

Figure 3 is a plan view of the connecting unit, the cover plate being omitted;

Figure 4 is a sectional view taken on line 4—4 of Figure 3;

Figure 5 is a central vertical sectional view;

Figures 6 and 7 are cross-sectional views taken 65 respectively on lines 6—6 and 7—7 of Figure 3;

Figure 8 is a sectional view taken on line 8—8 of Figure 5.

Figure 9 is a diagrammatic view generally similar to Figure 2 with a lift pump of the single-acting type (shown diagrammatically) added; and

Figure 10 is a diagrammatic view similar to that of the lower portion of Figure 2, but on an enlarged scale, with a lift pump of the double acting type (shown diagrammatically) added.

The immediate setting for the present invention is found in the operation of pumping systems—although the invention is itself not limited for use in this particular field alone. This particular field of service presents a number of problems which have tended to restrict the capacity of such systems, especially where the system is of the deep-well type, and while the art has developed solutions for some of the problems, certain of the difficulties have remained with the result that the capacity of the plants has been unduly limited, since efforts to increase capacity by increase in speed have resulted in loss of efficiency, etc.

One solution of the problems involved is presented in the disclosure of the companion application above identified, in which certain characteristics have been developed with a view to meeting one of the main difficulties that are presented—the activities within the end-zones of reciprocation of the driven member. While, in certain aspects, the present invention follows that particular arrangement, the present invention presents certain fundamental changes not only in structure but in theory, not only with respect to the disclosure of the companion application, but also from the practice that has been universally followed.

Like the companion application, the present invention contemplates the use of a reciprocating drive member driven from a suitable power source—preferably a source which translates rotary motion into the terms of the reciprocatory motion of the drive member; a driven member which is the power source for the pumping system—it may be the pump rod itself; and a mechanism which operatively connects the drive and driven members and is in the form of a leverage system which retains connection between the two members but which is subject to angularity variations during and by movement of the members with the leverage variations definitely controlled to set up a predetermined regimen in the relationship between the two members.

One of the advantages accruing from such arrangement is the fact that the drive member not only can be accurately arranged for true rectilinear motion through the fact that is of relatively short length, as compared with the driven member, but can have its movements controlled by the power source without undue likelihood of causing trouble in the end-zones of reciprocation, the stroke of reciprocation of the drive member being controlled wholly by the power source. Hence, the approach of the drive member to its extremes of reciprocation and the succeeding stroke start in the opposite direction can take place practically free from factors such as momentum, the travel of the power source through its zenith and nadir zones automatically developing the slow-down action during the approach and the pick-up action of the succeeding stroke without being affected by possible momentum, etc., of a moving body.

In contrast, the driven member may be of considerable or great length, a condition which not only makes it difficult to ensure accurate reciprocation, but which, because of its length, can develop various factors, such as "stretch," momentum, etc., matters which can be of extreme importance within the end zones of reciprocation, understandable from the fact that the power source, when passing the zenith and nadir points of its travel path, is travelling in an arcuate path and hence actually presents but

5 a theoretical and imperceptible inertia of rest period between the two periods of inertia of motion found in the opposite strokes of the reciprocating member. The direction of motion must reverse during this theoretical and imperceptible period, and the slightest lag of the driven member in making this change in direction during such imperceptible period of rest will affect the operation and cause difficulties and loss of efficiency. Because of this condition, the power source speed range has general limits beyond which it is unsafe to pass. Attempts have been made to meet the condition by the use of shock-absorbers and the like, but these set up other difficulties, with the result that the commercial practice has limited speeds to the safer zones.

10 In the companion application above identified, the problems set up have been met by providing a differential in speed between the two members during the approach to the extreme of reciprocation—reducing the speed of advance of the driven member within this end zone so that its rate of advance is materially less than that of the drive member. As a result, the power speed can be increased and still retain the approach speed of the driven member within the safe limits, thus increasing the capacity since the members, between the extreme zones, can travel at the higher speeds without causing difficulty. Such increase in speed can be had since, in such companion structure, the differential in speed relation during approach is necessarily present in the reverse relation at the beginning of the succeeding stroke, so that the speed increase does not tend to set up conditions of shock, etc.

15 The differential in speed condition referred to is provided, in the companion application, through the mechanism of the leverage assembly which connects the two members, and which has constant operative connection between the two members, but in which the angularity conditions are variable within the end zones, with the variations such that the distance travelled 20 per unit of time differs as between the two members within such end zones, the differential increasing in the direction of the extreme and reaching maximum within such extreme position; in the intermediate zone the two members travel at a one-to-one ratio, the differential developing and increasing to its maximum during the approach to the extreme of reciprocation. The control of the development of the differential is through the action of control faces 25 which govern the movement of the leverage carriers as the latter are moved by the drive member. As a result, the driven member approaches its extreme at greatly reduced speed as compared with the drive member, so that there is less likelihood of the development of the conditions which can develop the shock, etc., making it possible to operate the power source safety at higher speeds. The length of stroke of the driven member is reduced as compared with that of the drive member, but this offers no difficulty in connection with the installation of the system.

30 35 40 45 50 55 60 65 70 75 Like the companion application disclosure, the present invention deals with a generally similar problem, and utilizes a similar power source and drive member, with the driven member operatively connected to the drive member through a leverage assembly. In the present invention, however, the method of solving the difficulties

has been changed, and the sought higher-speed possibilities obtained in a different manner.

The underlying theory of the present invention rests on the fundamental condition that because the difficulties come through the necessity for requiring a complete reversal in direction of motion of the driven member during and within the theoretical and imperceptible period of inertia of rest, most of the difficulty can be overcome by providing a perceptible period of rest period at the extreme of reciprocation point, so far as the driven member is concerned, with the result that the driven member will have completed its stroke before beginning the succeeding stroke. Under such conditions, the beginning of the succeeding stroke need not overcome momentum or other lag-producing effects, and the load can be taken up with the lowered effort. In other words, by providing a momentary dwell at the end of the stroke of the driven member, any kinetic effects which may have been present will have reached an end, and the beginning of the stroke then takes place on the basis of the actual load rather than the load plus kinetic effects. It is apparent that if the momentary dwell period permits complete dissipation of any undesired kinetic effects, the fact that such effects may develop during the approach period becomes unimportant. As a result, the operating speeds of the system need not be limited to speeds such as would not present the possibility of excess kinetic effects, but can utilize speeds producing such effects without affecting the efficiency of operation.

The delay itself is but momentary—occupying but a few degrees of the arcuate travel of the power source—but its presence changes the driven member regimen from that of the drive member. For instance, assuming that the driven member approach is in one-to-one ratio with the drive member, the two members will approach the zenith or nadir positions of the crank-pin of the power source at equal speeds; but when the zenith or nadir points are reached, the drive member begins its stroke in the opposite direction as the crank-pin continues its travel, while the similar stroke of the driven member is momentarily delayed—assumedly the crank-pin will have advanced a few degrees angular distance past the zenith or nadir point during the delay, during which period the drive member has actually reversed its stroke and is beginning travel in the new direction, thus permitting the drive member to pass through the end zone changes in direction without the presence of the driven member load at the instant of change in direction; hence the drive member can be operated safely at the higher speed, due to its relatively short length; in addition, the distance travelled by the drive member in such advance is small, but it is sufficient to ensure that there will be no "luck" on the dead center point. Obviously, as the crank-pin advances, the speed of the drive member increases, and the period of delay would therefore set up the conditions of a "pick-up" of the load of the driven member, a condition that might imply the presence of shock conditions. But the invention is designed to meet this condition through the leverage action and in such manner as to retain the efficiency unaffected.

This is provided by affecting the speed of the driven member at the instant of the pick-up, making it a percentage speed of that of the drive member. For instance, the mechanism may set

up a two-to-one ratio (driven member speed as half that of the drive member) between the members at the instant of pick-up; or it may be a three-to-one or a four-to-one ratio between the members—the particular value is predetermined to meet the conditions of the particular installation. In other words, the rate of advance of the driven member at such time is but a percentage of that of the drive member, so that the drive member is not required to advance the driven member at its own speed at the time of impact, but at a reduced speed. After impact is had, the differential in speed between the members is gradually reduced until the differential is ended, and the two members travel the remaining distance of the stroke at the one-to-one relationship. It is possible for the control faces to be arranged to dissipate the differential in speed in any desired length portion of the stroke—the dissipation could extend throughout the length of the stroke, in which case the relative speeds of the two members would reach equality only during the approach; the particular arrangement in this respect will depend upon the particular conditions which are required to be met. In other words, the flexibility of the invention is such that it can be adapted to meet a large variety of conditions as to installations, since the particular formation of the control faces can be designed to meet the specific conditions set up by the installation.

The invention is shown diagrammatically in Figs. 1 and 2. Fig. 1 indicating the general set-up, with Fig. 2 presenting an enlarged showing of the mechanism zone, with the leverage carrier shown in different positions. In these views, A indicates the drive member and B the driven member, with the power source indicated as a rotating element C with a link L connecting the element with the drive member to set up the characteristics of a crank arm. With the drive member mounted for true reciprocation, it will be understood that the drive member movements will conform entirely to those produced by the power source, with the member reaching its extremes of reciprocation at the zenith and nadir points of arcuate travel of the crank. The drive member A thus will have its movements controlled wholly by the power source, and the approach and recession speeds will be in accord with those provided by the travel of the power source.

The driven member B is preferably in substantial alignment with the drive member A, and is also mounted for reciprocation; the specific structure of these members is presently described in greater detail, but at this point it is sufficient to indicate that the upper end of member B will be supported on a pin 10 which extends through a slot a of member A. Mounted on member A, and at opposite side zones of the latter, are a pair of arms or levers 11, each lever being provided with a roller 12 at its free end, each lever 11 being also provided with a link connection 13 with pin 10. The lever, roller and link connection on one side of the drive member extend at opposite angle to those of the other side, so that the two assemblies form what may be considered as leverage carriers symmetrically disposed to provide a connection between the drive and driven members.

The two leverage carriers provide a pair of swingable and articulable structures which connect the drive and driven members, each lever 11 being swingable on a pivot 11a carried by the

drive member and individual to the lever, while the free ends of the link connection 13 are mounted on pin 10 of the driven member. The two assemblies form a constant connection between the drive and driven members, but, as is apparent, the articulate connection can be made serviceable only if the leverage is definitely controlled. Such control is the function of the control faces 14 and 15, which are designed to be operative with the rollers 12 during opposite strokes of the members, face 14 serving as the control during the upward stroke in Fig. 1, and face 15 during the downward stroke in said figure. The two faces will in practice, be substantially duplicates, but oppositely disposed although this is not compulsory.

Each control face is active throughout the stroke length which it is to control, and is given a predetermined contour designed to set up the particular selected regimen of the stroke of the driven member. In the drawings—Figs. 1 and 2—the arrangement (which is illustrative only) is assumed to provide a two-to-one ratio at the beginning of the stroke, the contour at this point representing the position of the rollers 12 at the beginning of the stroke. The face 14 curves inwardly from this point—with face 15 curving outwardly from its corresponding point of the opposite extreme—to an intermediate point, after which the face continues parallel with the path of travel of the drive member. If a larger ratio is desired, a different curvature would be employed. Actually, each control face could be an uncurved, straight line face with the necessary inclination to set up the desired speed differential relationship; the curved form is preferred, as offering a smooth operating stroke in which the differential can be dissipated somewhat prior to the end of the stroke.

As will be seen, the two faces are so related that when the roller 12 is in the position X—which is assumed to represent the lower extreme of reciprocation of the driven member—the roller is in contact with the curved portion of face 14, and is just out of contact with the straight portion of face 15. The particular distance between the faces at this point will be properly selected, but, in practice, it would be such as to leave a slight space between the roller and face 15 when the roller contacts face 14 in this position; for instance, if the roller be of two inch diameter, the spacing of the faces at such point would be approximately $2\frac{1}{64}$ inches. In other words, the arrangement is such that at no time does the roller bridge the space between the faces, but in the positions which represent the two ends of the stroke of the driven member, the spacing of the two faces approaches the diameter of the wheel dimension but is sufficiently larger as to assure definite clearance between the roller and face 15 in this position.

This spacing is designed to provide the delay period referred to. During the downward travel of the drive member, roller 12 travels in contact with face 15. When the lower extreme of drive member stroke is reached, the leverage carrier ends its downward movement—but with the roller still in contact with face 15. As the drive member passes its nadir point and begins its upward stroke, it draws on lever 11, but at such time the resistance of the driven member is present, and since roller 12 is out of contact with face 14 at the instant of change, the resistance and power are effective in opposite directions with the result that these forces will cause roller 12 to

leave face 15 and pass into contact with face 14. The time required to make this shift represents the delay period referred to.

The shift in position of roller 12 takes place through the travel of the drive member, so that the latter will have advanced a slight distance on its upward stroke at the time the roller contacts face 14; the distance is small—a few degrees of arcuate travel of the power crank pin—but the crank pin will have passed its dead center position and therefore is exerting an upward pull with the pull active on the leverage carrier. Initially, the pull is active to shift roller 12 from contact with face 15 to its contact with face 14, as before explained, the resistance of the driven member causing the link 12 to rock lever 11 on pivot 11a to draw the roller inward, until contact of the roller 12 with face 14 causes the carrier to present the characteristics of a lever of the second order which, when established, causes the pull of the drive member to be communicated to pin 10 through the link connection 13.

However, due to the curvature of face 14, this upward travel of lever 11 and roller 12—in presence of the resistance of the driven member—changes the angularity of lever 11 and consequent change in angularity of the link connection 13, so that the distance traveled by the driven member per unit of time is less than that of the drive member, the value of the differential being determined by the position of the roller on face 14. At the beginning of the stroke the ratio illustrated would approximate a two-to-one ratio. As the roller advances, however, the changes in leverage angularity of lever and link gradually set up the condition where the differential is completely dissipated, so that when the roller 12 reaches the parallel position, the two members travel at equal speeds and distances during the remainder of the stroke, due to the constancy of the leverage positions during the latter portion of the stroke.

When the crank-pin reaches its zenith point—presenting the upper extreme of reciprocation of the drive member—the driven member will also have reached its upper extreme, with the roller still in contact with face 14. However, when the drive member begins its return stroke after passing the zenith, the resistance of the driven member again becomes effective in opposition to change on the part of the driven member, with the result that the downward movement of the lever 11 will be resisted by pin 10, acting through link 13, thus rocking lever 11 to carry roller 12 into contact with face 15, thus setting up the latter as the control face during the succeeding downward travel of the carriers, and during which the initial two-to-one ratio becomes manifest and is followed by the gradual dissipation of the differential as described in connection with face 14.

As is apparent, the length of the stroke of the driven member is less than that of the drive member, the difference in stroke length being determined by the selected ratio and the length of the zone of dissipation of the differential; during travel within this zone, the speed of the driven member is less per unit of time than that of the drive member, so that the distance travelled is less. However, this fact is not detrimental, since it is obvious that the power source and drive-member stroke will be arranged to provide the desired length of driven member stroke.

In other words, the time length of the stroke cycle of both members is the same, but the start

of the driven member cycle is given this delay period referred to, and is then started at the percentage rate which is then accelerated until the speed parity with the drive member is reached.

As is apparent, the shift of the roller 12 from one face to the other is provided by the resistance of the driven member opposing the change in direction which has been made by the drive member. Such resistance is present where the installation is that of a double-acting pumping system in which the pumping element is in pumping activity during both strokes. Because of this the present invention is especially applicable for service in this particular field of pumping activity. However, it is not limited to such field, since it is also applicable for use with single acting pumping systems. In the latter, the load would be present with the upward stroke, so that during such stroke the conditions would not change. Since, however, the resistance due to pumping action is absent during the downward stroke with a single-acting pump, the weight of the driven member would remain present as a factor tending to move the driven member downward, additional to the drive member. This might lead to the assumption that this force, drawing on pin 10, would cause link 13 to draw lever 11 inward and cause the downward travel of the leverage carrier to be controlled by face 14.

However, the latter condition is actually not present. When the driven member begins its downward stroke from its upper extreme of reciprocation, the pumping valve opens, and the area of this valve is always less than the cross-sectional area of the pumping cylinder, with the result that there is developed a resistance value due to the effort to displace a larger fluid volume through a smaller port; where the driven member is of a type in which the weight factor is insufficient to overcome this resistance, the structure will operate similarly to the double-acting pumping system regimen. Should the driven member be of a type which would so increase the weight factor as to overcome this resistance value, the condition is met through the addition of a spring 16 between the drive and driven members, such spring opposing the tendency of the weight factor to draw the driven member downward at a speed such as to draw the roller in from face 15, the spring tending to act as a resistance opposed to the excess of the weight factor over the resistance value. If spring 16 be of the expansion type, its greatest resistance will be in the upper zone of the travel of the drive member; if the spring be of the compression type, the greatest resistance will be in the lower zone of such travel. This is due to the fact that the angularity of link 13 changes as the roller 12 traverses the curved portion of the control face, the angularity of the link to the horizontal being greatest during travel of the roller over the portion of control face 14 extending parallel to the path of travel of the drive member, this angularity decreasing within the curved portion of such face; as a result, the distance between the attaching points of the spring on the two members will be least at the lower extreme of reciprocation, and greatest at the upper end of the curved portion of face 14, since travel of the roller toward this point has the effect of increasing the angularity of the link to the horizontal; the angularity of the link remains constant during travel of the roller over the straight portion of the face 14 toward and to the upper extreme of reciprocation. Similarly, the

reverse action takes place during downward travel of the roller over the curved portion of face 15—the angularity of link 13 to the horizontal becomes static when the straight portion of this face is reached.

Should, however, the conditions arise that the weight factor overcome the resistance during such downward travel—with a resultant inward drawing of roller 12 to contact face 14, the operation is not fatally affected, since the inward movement of roller 12 will then bring the roller into contact with face 14, and further downward travel will then be under the control of the latter face, and present the conditions produced by the structure of the companion application—causing the approach to the lower extreme of reciprocation of the driven member to be made under the conditions of a differential of speed relative to the drive member. At the end of the drive member stroke, the roller will have the same position as at the beginning of the return stroke—as will pin 10 due to the fact that travel of roller 12 in contact with face 14 will cause the change in angle of the leverage to decrease the stroke of the driven member the same value as is present with the regular regimen; the one effect could be the reduction of the length of the delay period or its elimination during the particular cycle in which the condition arose—the new cycle of the driven member would begin earlier. The condition indicates the factor of safety that is present.

The above explanation will be clearly understood from the showing of Figs. 9 and 10, which present a conventional showing of a single acting lift pump (Fig. 9) and a double acting lift pump (Fig. 10) as a continuation of the disclosure of Figure 2.

For instance, in Fig. 10, it is apparent that each stroke of the piston is an active stroke—drawing in a supply to one side of the piston and discharging the content from the opposite side of the piston, the valves being shown as balls located in cages. Since pressure is required to move the piston in either direction, the pump provides a resistance active to resist a change in direction of the stroke, effective in both extremes of reciprocation of the piston, thus setting up the conditions which cause shift of contactor 12 from one control face to the other as explained above.

In Fig. 9 the showing is that of a single acting lift pump (shown conventionally) with the valves shown as of the pivoted or flat type, one of which controls a port through the piston. During the up stroke the content above the piston is being discharged into the outlet—the piston valve is closed—while the piston draws in fluid into the space below the piston; during the down stroke the supply valve is closed as is the outlet valve, while the piston valve is open, so that, theoretically, the piston is simply travelling through the content placed below the piston during the previous stroke; theoretically, this displacement of the piston would be under "unloaded" conditions, and thus without material resistance effect; but the difference in area between the piston and the port therethrough actually provides, in practice, the resistance values desired in the upper extreme where the piston changes from the up to the down stroke—in the lower extreme the normal loaded condition of the pump provides the resistance effect. As a result, the contactor 12 is shifted to the

opposite control face in both of the extremes of reciprocation of the drive member and the unit carrier A.

Figures 3 to 8 present an illustrative form of structure of the unit assembly which may be employed in carrying out the invention. The actual structure may have a number of different forms depending upon the specific installation being provided, the structure disclosed presenting a simple arrangement which will indicate the underlying characteristics present, and is therefore more or less illustrative of such various forms.

The control faces 15 are shown as the inner faces of side walls of a casing 20, the latter having end walls 20a and 20b arranged with aligned openings to receive ways 21, 21 which are spaced apart to receive and guide a carrier 22 which, in effect, is the portion of the drive member A operating in the casing; the upper end of the carrier has an operative connection with the power source through link L. Obviously, the casing may be independent of faces 15, if desired; and, similarly, ways 21 may be integral with the casing end-walls. The outer faces of ways 21 may form the straight portions of control faces 14, in which case the curved portion of such control face would lead from such way face and be connected to the bottom wall of the casing; obviously, control face 14 may be provided by a face completely separate from a way 21.

The carrier 22 is provided with an elongated recess 22a, shown as extending inward from its lower end, said recess being adapted to receive a slidable element 23; the recess is of greater length than the element, and the recess end is closed by a closure 22b; element 23 is designed to support pin 10 and form an extended structure which will ensure travel of the pin in a true rectilinear path during the operation of the unit as presently described in detail. The carrier 22 is also provided with a slot 22c on the forward and rear faces, these slots extending into the recess; the slots 22c permit the movement of the pin 10 relative to the carrier in a longitudinal direction of the latter. While the carrier is shown as having a slidable mounting in the ways 21, and the element 23 has a similar mounting in the carrier, it will be readily understood that, to decrease friction, the carrier may have rolls mounted to contact the ways 21, and the element may carry rolls contacting the walls of the recess, this being an obvious anti-friction arrangement which may be employed.

The levers 11 may have any desired structural arrangement, the drawings illustrating each of them to be of fabricated type through making each lever in the form of a pair of arms 24 connected respectively to the front and rear faces of the carrier by a pin 11a and which have their free ends supporting roller 12 which is mounted between the arms. Each arm has a link connection with pin 10, so that each link 13 thus becomes a fabricated structure which has a connection with pin 10 on both the front and rear faces of the carrier, pin 10 having a length sufficient to receive the links from both sides of the unit outside of the carrier, suitable securing devices being employed; by this arrangement the power applied to the pin from the drive member is made effective to ensure that no torsional effects are placed on the pin during operation.

It is apparent that while the rollers 12 traverse the straight portions of control faces 14 and 15, the levers 11 do not change their angularity to the path of movement of the carrier; and since the links 13 are of constant length, the angularity of these links to the horizontal does not change, since the paths of travel of the pin 10 and the pivots on which the links are secured to arms 24 are then parallel. However, as soon as the rollers pass on to the curved portions of the control faces 14 or 15, the roller tracks the face with the result that the travel of the pivot of the links on the arms varies from such parallel travel path, with the result that the angularity of the links 13 is varied, since the constant distance between the link pivots and the location of the pin forces the pin and its supporting element 23 to move in recess 20c and relative to the carrier, the length of such relative movement depending upon the length of travel of the roller 12 along the curved portion of the control face. For instance, in Fig. 8 the roller is shown at an intermediate position; if the carrier is moved upward, the roller face contacts a portion of the control face closer to the axis of reciprocation, and the angularity of the links to the horizontal will increase, thus causing the pin 10 and its supporting element to travel downward in the recess and slots relative to the carrier, although both elements may be actually travelling in the same direction—the rate of advance of the pin is reduced relative to that of the carrier. On the contrary, if the movement of the roller is downward from the position of Fig. 8, the distance of the roller from the axis of reciprocation is increased, and the links 13 will have their angles varied to the horizontal in a direction to cause the pin 10 and its supporting element to move upward relative to the carrier, although both may be moving downward.

As will be understood, the inclination of the links 13 will depend upon the location of the outer pivots relative to the axis of reciprocation—the inner pivot (the connection of link and pin 10) is located in the axis of reciprocation, so that the distance of the outer pivot from such axis will control the link inclination; with the relation of the outer pivot determined by the arm 11, it is apparent that as the control face contour changes the distance between the roller and the axis of reciprocation, such change becomes effective to shift the position of the outer link pivot, as the distance is increased or decreased. This distance remains constant on the portions of the control faces which extend parallel with the axis of reciprocation—thus retaining the angularity of the links constant in this zone; when, however, the roller traverses the curved portions of these control faces, the angularity of the links change, thus causing pin 10 and its supporting element to be advanced or retarded with respect to the carrier, but without breaking the drive relationship between the carrier and pin, even though there is a momentary break in the support for the roller at the instant of reversal of the stroke of reciprocation provided by the shift of the roller from one control face to the other; during the break in support, the connection between carrier and pin remains constant, but becomes inactive as a driving medium for the pin during the period when the roller is out of contact with either face—a momentary period, due to the fact that the two faces in the extremes of re-

ciprocation are spaced a distance only slightly greater than the roll diameter.

As pointed out above, the shift of the roller from one face to the other is provided by the fact that the direction of travel of the drive member is suddenly reversed by the movement of the power source through the zenith or nadir points. At such time of reversal of the stroke of the drive member, the same reversal will take place in the pin 11a of arm 11, but to provide a simultaneous reversal of the stroke of pin 10, the roller 12 would need to provide a positive resistance in order to force the pin to move; at this instant—the moment of change of drive member stroke to its new direction—the control face active during the approach of the driven member becomes inactive, provided there is any resistance value to change in stroke direction by the driven member. With a double-acting pumping system, such driven member resistance is present on both strokes—in single-acting pumping systems, the smaller valve opening provides a resistance as explained above. Hence, at the instant of change of the stroke of the drive member, the driven member resistance becomes active in opposition to the change with the result that the link becomes active on the arm to force the roller away from its previous control face, this movement continuing until the roller contacts the other control face and thus sets up a resistance against further yield of arm 11; when this occurs, the drive effect of the drive member again becomes active on the pin 10, and the driven member, with the newly-active control face determining the position of the roller as the drive member continues through the stroke.

As pointed out above, under single-acting pumping systems, it may be desirable to add a spring 16 in order to afford an additional resistance to the driven member during the downward stroke of such driven member, this being the idling stroke with such systems. The spring may be of the tension or the compression type, as before indicated, and need not present a large power value, since it is used only to augment the normal resistance provided by the smaller valve opening. The spring operatively connects the drive and driven members, if of tension type, or is located between the members if of compression type. For purposes of illustration the spring effect is illustrated in dotted lines in Fig. 3, by a pair of springs connected to opposite side portions of one or both arms 25 of the driven member and leading to suitable points on the carrier; the connection may be of any suitable form—as by hooks carried by the ends of the springs. With double-acting pumping systems such spring structure is unnecessary.

The driven member B is illustrated only by its upper end portion, this being represented by the arms 25 which, as indicated in Fig. 4, extend downward from pivot 10; the lower ends of the arm will be secured to the upper end of the pump rod which therefore completes the driven member. This provides a simple arrangement of unit assembly and assures the essential strength and rigidity in service.

The fabricated form of structure enables the unit to be readily constructed with the dimensions arranged to meet the individual installation. If desired, suitable anti-friction rollers or other structures may be utilized, and, if desired, the unit casing may be arranged to contain lu-

bricant, in which case the movements of the parts would be in an oil bath.

As will be understood, the distance of the straight portion of control face 15 from the axis of reciprocation is never greater than can be bridged by the linkage without bringing link 13 actually to the horizontal. In other words, the length of such links is such that when the levers 11 are swung outward to the greatest distance permitted by control face 15, the links 13 will still remain angular to the horizontal—the links never reach a position where they could shift to the opposite inclination; while the angularity of the links to the horizontal may vary, as pointed out, the variations take place always on the same side of the horizontal.

As will be apparent, the length of the dwell period of the driven member is controlled entirely by the spacing of the two control faces at the extremes of reciprocation; a slight increase over the diameter of roller 12 is sufficient—any increase serving to increase the length of dwell. This is due to the fact that the power source causes carrier 22 to begin movement in the reverse direction while pin 10 remains stationary due to the resistance of the driven member; as a result, opposing pressures are placed on the link pivot to the arms in a direction opposing that which would be required to apply power from the carrier to pin 10. As long as the arms can swing under such action, the power effect of the carrier is inactive on the pin; the inactivity ends when roller 12 contacts the control face toward which the arms are swinging; when contact is had, the leverage becomes active to transmit power to the pin.

During this period inactivity of transmitting power to the pin 10, the carrier continues its movement in the new stroke, due to the fact that the power source continues its travel past the zenith and nadir points. Hence, the number of angular degrees which will be traversed by the power source during the period will depend upon the distance which must be travelled by the roller when shifting from face to face—the greater the distance the greater becomes the angular distance travelled by the power source. In practice, the distance is preferably slight, since the number of angular degrees need not be large in order to provide the dwell action that is desired to assure that the drive member has actually reached the condition of inertia of rest before again resuming the inertia of motion status; a slight distance of travel by the roller will provide this result, and restore the power transmission before the carrier has reached a speed of advance such as would impart a shock action at the instant the power becomes active on the driven member.

While I have shown and described the invention as used in connection with pumping systems, it will be readily understood that the invention is not limited to this particular field, but is applicable for use wherever the conditions of a reciprocating drive member is used for driving a reciprocating driven member in the operation of a particular mechanism, and especially where the driven member characteristics are such that the possibilities of detrimental kinetic energy developments tend to reduce the possible operating speeds. The possibility of using a drive member of short length and light weight, as well as the ability to mount such member in such manner as to ensure travel only in a reciprocatory path and with a minimum of resistance in its

own operation—thus practically eliminating the development of detrimental kinetic energy within itself, and therefore sensitively responsive to the control of a rotative power source—makes it possible to utilize the invention and obtain higher speeds of operation where the driven member is such as would develop detrimental kinetic energy at higher speeds in the absence of the invention. By interposing the delay period between the two periods of inertia of motion, assurance is had that the detrimental kinetic energy will be dissipated even at the higher speeds of operation, and thus increase the capacity of the mechanism so equipped with the invention.

The above disclosure generally contemplates the use of control faces 14 and 15 designed to present like action with both strokes of the driven member; the values of the differential speed relationships between the drive and driven members, and the range of the zone of such differential status, may vary to meet the conditions of individual installations, but the contemplation is that these values are similar in both strokes of the driven member, this being the preferred arrangement.

However, installation conditions may be such as to make it advisable to provide different values to the two faces, and such variation is also contemplated within the present invention. For instance, where the power source moves in a circular orbit and the driven member is driven thereby, the arrangement of the latter is generally with the power source connection located at the opposite end of the driven member to that of the pumping piston; under such conditions, one stroke of the driven member is under the conditions of "pull" and the opposite stroke under the conditions of "push." With a driven member of considerable or great length, it would be difficult to set up an assemblage in which the member is supported against bending or buckling throughout its length, if the operating conditions were such as to provide opposing pressures such as to cause bending or buckling intermediate the ends of the driven member—as when the resistance value of the piston as opposed to the speed value of the power source are such that the driven end of the driven member would materially overrun the speed of the piston permitted by the resistance.

The possibilities of such conditions are greatest at the mid-zone of the travel of the crank pin between nadir and zenith positions, and the present invention contemplates meeting the possibilities by including such mid-zone within the range of the differential speed relationship; in such case the speed of the driven member does not reach the maximum value of the drive member, since the two members come into the one-to-one drive relationship only when the crank pin has reached a point in its orbit where the speed of the drive member is decreasing. Such conditions are within the above contemplation.

However, it is obvious that the undesired pressure conditions could occur only during the "push" stroke of the driven member—as where the pumping system is of the double-acting type—since bending or buckling would not occur when the member is being pulled; hence, the operating conditions between the two strokes present different conditions under such circumstances. It may be desirable, for operating conditions that during the "pull" stroke the range of the differential zone may be greater or less than during the "push" stroke. For instance, with a

driven member in which the weight factor is reduced, the possibilities of bending or buckling would be increased during the down stroke while it would be possible to set up the one-to-one drive relation between the members at an earlier period during the "pull" stroke—in such case the differential speed value and range within which it is made manifest can be made different as between the control faces, face 15 being arranged to provide a range such as to avoid the development of material bending or buckling, while the contour of face 14 would be arranged to meet the more favorable conditions provided by the "pull" stroke. Or, on the other hand, the driven member may have a structure and weight factor which is least likely to bend or buckle, but which could provide a material weight factor active in opposition to the power; in such case the contour of face 14 could be arranged to present the greater values as to differential in speed and range, and thus tend to set up an increased, power factor active during the pull stroke.

These present but a few of the possibilities of installation problems, and are being referred to specifically to illustrate the extreme flexibility of the invention through the ability to control the contours of the control faces 14 and 15 to meet individual problem characteristics of a particular installation.

The specific structure shown is more or less illustrative, being a simple and compact arrangement which is capable of carrying out the underlying fundamentals of the invention. The fabricated form of the links and levers is shown since they can be in the form of stampings. However, it is apparent that the character of the installation will control the physical structure to be employed, as well as the form and dimensions of the various elements employed, similarly, the individual preferences of the engineer as to these characteristics can lead to preferred modifications. I therefore desire to be understood as reserving the right to make any and all such variations and modifications thereina as may be needed to meet these conditions, insofar as the changes and modifications may fall within the spirit and scope of the invention as expressed in the accompanying claims, when broadly construed.

50 I claim:

1. In motion transmitting mechanism, a reciprocatory drive member, a power source operative to provide and control the timing and length of reciprocation of such drive member, a reciprocatory driven member in general alignment with the drive member, and a leverage unit operatively connecting the reciprocatory drive and driven members, said unit having a direct drive connection with such drive member to thereby bodily reciprocate the unit in synchronism with the drive member and having direct connection with the driven member to thereby drive the latter, said unit including means operative to vary the drive relation between the members by varying the leverage angularity of lever elements to thereby control the movement of the driven member, said drive and driven members and said unit being co-related in operation to provide the following sequence of reactions by the driven member to the reciprocation movements of the drive member: during approach of the drive member to its extremes of reciprocation the driven member approach to its extreme of reciprocation is concurrent therewith and at a definite speed ratio thereto; during the succeed-

ing change in direction of stroke of the drive member, the beginning of the stroke of the driven member is delayed with respect to the beginning of the drive member stroke to permit dissipation of kinetic energy of the driven member; then begin the driven member stroke under the conditions of a predetermined percentage speed ratio relation with the drive member; and thereafter completing the driven member stroke by varying the speed ratio between the drive and driven members until the ratio becomes that of the approach period.

2. Mechanism as in claim 1 characterized in that the speed ratio between the drive and driven members during the approach period is substantially one-to-one, and with the speed of the driven member stroke beginning as less than that of the drive member in a ratio of at least two-to-one.

3. Mechanism as in claim 1 characterized in that the power source and drive member are operatively connected to provide the relationship of converting rotary motion of the power source into reciprocatory motion of the drive member, with the extremes of reciprocation of the drive member provided by the zenith and nadir points of the power source movement, the delay period of the driven member beginning at such zenith and nadir points and continuing during the advancing travel of the power source from such points for a few degrees of angular travel of the source.

4. In motion transmitting mechanism, a reciprocatory drive member, a power source operative to provide and control the timing and length of reciprocation of such drive member, a reciprocatory driven member in general alignment with the drive member, and a leverage unit operatively connecting the reciprocatory drive and driven members, said unit having a direct drive connection with such drive member to thereby bodily reciprocate the unit in synchronism with the drive member and having direct connection with the driven member to thereby drive the latter, said unit including a lever pivoted to the drive member and carrying a contactor at its free end, a link pivotally connecting the driven member with an intermediate point of such lever, and a pair of control faces extending in opposed relation at opposite sides of the contactor, each face having a contour such as to control the leverage angularity of the lever and link assemblage by the travel of the contactor over the face of drive member movements, said faces being relatively spaced as to prevent concurrent engagement of the contactor with both faces during a stroke of the drive member, said contactor being shiftable from engagement with one control face to engagement with the other control face within the end zone of reciprocation of the drive member.

5. Mechanism as in claim 4 characterized in that the contour of each control face is such as to provide a definite speed relationship between the drive and driven members during the approach of the members to their extremes of reciprocation, and a predetermined percentage differential speed relationship between the members at the beginning of the stroke of the driven member.

6. Mechanism as in claim 4 characterized in that the contour of each control face is such as to provide a substantially one-to-one speed relationship between the drive and driven members during the approach of the members to their

extremes of reciprocation, and to provide a differential speed ratio between the members at the beginning of the driven member stroke with the drive member speed at least of two-to-one 5 relation to the speed of the driven member, and with the face contour operative to dissipate such differential during the travel of the contactor to such approach zone.

7. Mechanism as in claim 4 characterized in 10 that a control face is active with the contactor substantially throughout the length of a stroke of the drive member, with the activity of one face controlling in one direction of reciprocation and the activity of the other face controlling in 15 the opposite direction of reciprocation.

8. Mechanism as in claim 4 characterized in 20 that a control face is active with the contactor substantially throughout the length of a stroke of the drive member, with the activity of one face controlling in one direction of reciprocation and the activity of the other face controlling in 25 the opposite direction of reciprocation, the shift of the contactor from one face to the other being provided by the change in direction of reciprocation by the drive member combined with the resistance of the driven member to such change.

9. Mechanism as in claim 4 characterized in 30 that the power source is of the rotating type and operatively connected with the drive member to translate the rotary motion of the power source into reciprocatory movement of the drive member, each control face controlling the contactor during a stroke of the drive member with the contactor shiftable to engage the other face for control of the stroke in the opposite direction, said shift of the contactor being provided by the movement of the power source through the zenith and nadir points of power source travel 35 combined with the resistance of the driven member to change in direction of reciprocation.

10. Mechanism as in claim 4 characterized in 40 that the driven member is the actuating element of a pumping system of the double-acting type, said mechanism acting through a control face and the contactor to control the relative speeds of the drive and driven members during and through a pumping stroke, the resistance in the pumping system incident to the beginning 45 of the succeeding pumping stroke being operative to shift the contactor to the other control face for control of the speed relation during the succeeding pumping stroke, the contactor shift being operative to produce a delay period in the beginning of the stroke of the driven member 50 during continuance of the drive member activity.

11. Mechanism as in claim 4 characterized in 55 that the driven member is the actuating element of a pumping system of the single acting type, said mechanism including a resistance structure between the driven and drive members, a control face and the contactor being active in the control of the relative speeds of the drive and driven members during and through a pumping stroke of the driven member, said resistance structure and the resistance present at the beginning of the succeeding preparatory stroke of the pumping system being operative to shift 60 the contactor to the other control face for controlling the relative speeds of the members during the idling stroke, the contactor shift being operative to produce a delay period in the beginning of the stroke of the driven member during 65 continuance of the drive member activity.

12. Mechanism as in claim 4 characterized in that the lever is of fabricated spaced-ply type with the roller located between plies, the link is of similar type with the link plies overlying the lever plies, and that the adjacent end of the driven member is of similar type, having its plies overlying the link plies at the point of connection of links and driven member.

13. Mechanism as in claim 4 characterized in that the contour of each control face is such as to provide a definite speed relationship between the drive and driven members during the approach of the members to their extremes of reciprocation, and a predetermined percentage differential speed relationship between the members at the beginning of the stroke of the driven

member, the contours of the opposed control faces presenting like values throughout the length of the faces.

14. Mechanism as in claim 4, characterized in that the contour of each control face is such as to provide a definite speed relationship between the drive and driven members during the approach of the members to their extremes of reciprocation, and a predetermined percentage differential speed relationship between the members at the beginning of the stroke of the driven member, the contour of one of the opposed control faces presenting a different value of speed relationships and/or range of such relationship from that presented by the opposed control face.

BRYAN BRASSELL.
